UNITED STATES PATENT OFFICE.

POWEL CROSLEY, JR., OF CINCINNATI, OHIO.

VARIABLE INDUCTANCE.

Application filed November 3, 1923, Serial No. 672,491. Renewed October 5, 1928.

My invention relates to apparatus for coupling electrical circuits inductively, more especially circuits of low voltage, as in radio apparatus and the like.

5 The object of my invention is to provide a simple, compact and inexpensive device of this character, permitting the degree of coupling of the circuits to be varied through a wide range with infinite number of adjustments within the range of adjustment, by very simple manipulation without liability of derangement, so that the device is readily installed and operated by relatively unskilled users. Other objects will appear in 10 the course of the ensuing description.

I attain these objects by the device illustrated, for example, in the accompany drawings, in which—

Figure 1 is a side elevation, with part of 20 the panel mounting shown in section;

Fig. 2 is an inverted plan view of the same, with the part of the panel mounting in section;

Fig. 3 is a vertical cross-section on the 25 plane of the line 3—3 of Fig. 1, further illustrating the arrangement of the spring for maintaining the adjustment of the device, the panel mounting being omitted;

Fig. 4 is a detail perspective view of the 30 spring;

Fig. 5 is a rear end elevation of the device; and

Fig. 6 is a vertical longitudinal section 35 of a modified device embodying my invention.

As shown in Figs. 1 to 5, inclusive, a bracket 1 is formed of heavy sheet metal 40 bent to form yokes 2 and 3 at the front and rear ends, respectively, at right angles to the main part 4; each yoke having a middle square opening 5. The front yoke 2 has its opposite ends in the form of ears 6 projecting laterally past the main part 4, and each ear has a tapped hole through it, receiving 45 a screw 7. These screws 7 pass back through the panel 8, and have flat heads sunk in the front of the panel so that the knob 9, fixed on the front end of the square shaft 10 sliding snugly in the square openings 5, may 50 come back closely against the front of the panel 8.

The rear yoke 3 has similar ears 11 at its opposite ends, each having a tapped hole through it. The core 12 comprises a central

hub part 13 from which radiate a plurality 55 of arms 14 of the same thickness as the hub part 13, which latter has a central opening registering with the square opening 5 of the rear yoke 3 when the core 12 is secured to this yoke by screws 15 passed forwardly 60 through holes in the hub part 13 and screwed into the tapped holes in the respective ears 11 of the yoke 3.

The spring 16 is formed from flat resilient sheet metal with flat members 17 inclining 65 down laterally from a middle ridge 18 and terminating in narrow depending flanges 19 which flank the main part 4 of the bracket 1 and lie closely against the respective lateral edges thereof, while the ridge 18 bears upward against the bottom of the square shaft 10 and the lower sides of the members 17 of the spring, adjacent to their junctions with the flanges 19, bear along the respective upper corners of the edges of the main part 70 75 4 of the yoke, as clearly seen in Fig. 3.

The square shaft 10 extends back past the core 12, through the central opening thereof, and has its rear end reduced to form the cylindrical threaded part 20 and a shoulder 80 21 therearound, against which is a washer 22 around the part 20. The movable core 23 is similar to the above described core 12, with a hub part 24 and radial arms 25 of uniform thickness; this core having a tapped hole centrally of its hub part 24 which receives the threaded end part 20 of the shaft 10 and the core being screwed forward firmly against the washer 22 and held in that 85 position by a nut 26 screwed on the part 20 with a lock washer 27 between the nut and the core 23. As shown, this rear movable core 23 has its arms 25 shorter than the arms 14 of the front fixed core, in accordance with the requirement for less space thereon than 90 on the fixed core. Diametrically opposite holes 28 in the hub part 24 of the rear movable core 23 serve for passage of the terminals of the conductor carried by the core.

The front fixed coil 29 has one terminal 30 leading from the base of one of the core arms 14 and is passed spirally around its core 12 and across the arms 14 thereof until its last turn passes through a small hole 31 in the outer end part of one of the arms 14, 100 preferably, as shown, the arm at which the winding begins as just mentioned; the part 105 of the coil extending from this hole 31 forms

ing the other terminal 32 of this coil. It will be understood, however, as is well known, that this coil 29 may be tapped at various points throughout its extent of 5 winding, as at 33 in Fig. 2, by leaving extensions 34 and 35 to lead to a suitable tap switch, which, being well known, is not illustrated. Such tapping preferably is made adjacent to the same arm 14 at which 10 the winding begins and ends as before mentioned.

The rear movable coil 36 is similarly wound on its core 23, but the inner end part 37 preferably is connected to a terminal 15 wire 37' inside a suitably insulated tube 38 through which the wires are carried across the front of the hub part 24, permitting the terminal wire 37' to pass rearwardly out of this tube 38 through one of the holes 28 in the core 23; and the outer end part 39 of the coil 36, after passing through a small hole 40 in the outer end part of the arm 25 at the base of which the winding starts, is connected to a similar terminal wire 39' inside 20 a similar insulating tube 41, through which the wires lead across the hub part, with the terminal wire 39' passing out of the tube and back through the other hole 28 in the core 23. Preferably, these terminal wires 37' 25 and 39' are more heavily insulated and more flexible than the wire of the coil 36, to withstand the handling required for connection to apparatus with which the inductance is to be installed.

35 The square shaft 10, guided in the square openings 5 of the bracket 1, with the movable coil fixed against rotation, maintains the relative angular positions of the coils, preventing mechanical injury to the terminal 40 connections such as may occur with a round shaft which allows the operator to turn the knob 9 while adjusting the device. The apparatus is illustrated and described as with the shaft 10 horizontal, but in some 45 installations it may be vertical, mounted on a horizontal panel or the like, for up and down adjustment. In either case, the spring 16, with its parts 17 flexed apart and forcing the ridge part 18 against the shaft 10 by 50 their reaction against the edge parts of the bracket 1, and held from sidewise displacement by the flanges 19 at these edge parts, will hold the movable coil in adjusted position, yet allow ready movement thereof by 55 simply pulling or pushing on the knob 9.

In the example of Fig. 6, the square shaft is employed in conjunction with inductance coils of a different disposition. A tubular core 42 has one end fixed to the upright 60 panel 43 by small brackets 44. Centrally of this core a bearing bushing 45 has a part passed through an opening in the panel 43 and a head against the front of the panel; the passed through part having threads receiving a nut 46 screwed against the rear

side of the panel, firmly fixing the bushing 45 therein. This bushing has a square opening 47 receiving the square shaft 48 to slide snugly therein, with the knob 48 on its front end in front of the panel 43, and having its 70 rear end reduced forming the cylindrical threaded part 49 on which is screwed the movable core 50 in the form of a spool of great diameter relative to its axial length. This spool is firmly held by the nut 51 and 75 lock washer 52 in a manner similar to the mounting of the movable core in the previous example.

This movable core 50 carries the movable inductance coil 53 wound therearound, at a 80 diameter such that this coil is carried very close to the inner wall of the tubular fixed core 42, which wall is relatively thin, permitting close approach of the movable coil 53 to the fixed coil 54 wound on the exterior 85 of the tubular core 42. A flat spring 55 has one end part embracing the threaded rear projection of the bushing 45 and clamped against the rear of the panel 43 by the nut 46; the other end part of the spring having 90 a bend by which it presents a curved surface against the top of the square shaft 48. This modified device may be mounted horizontally as shown, or with the shaft 48 upright, for up and down adjustment; 95 in either case the spring 55 holding the movable coil in adjusted position, and the square shaft with the movable core or spool 50 fixed thereon preventing turning of the movable coil 53 and derangement of its exterior 100 connections, as in the preceding example.

Other modifications may occur, in conjunction with different installations, or to meet varying requirements, and therefore although I have rather specifically illustrated and described certain preferred details of construction of my invention, I do not wish to be understood as being limited to such precise disclosure, but having thus fully 105 described my invention, what I claim as new and desire to secure by Letters Patent is:

1. In a device of the character described, the combination with relatively movable 110 coils, of a shaft of angular cross-section supporting one of the coils, means fixed to the other coil and having a bearing holding said shaft for non-rotative longitudinal sliding in said bearing, and having edges substantially parallel with said shaft, and a 115 spring formed of a flat sheet bent with members meeting in a ridge bearing along said shaft and with flanges lying along said edges of said bearing means.

2. In a device of the character described, the combination with two coils, of a shaft of rectangular cross-section supporting one of the coils, a bracket fixed to the other coil and having extensions spaced longitudinally 120

of the shaft, with rectangular openings in the extensions holding the shaft for non-rotative longitudinal sliding in said bracket, the part of the bracket between said extensions having edges substantially parallel with said shaft, and a spring formed of a flat sheet bent with members meeting in a ridge bearing along said shaft and with flanges lying along said edges of said part 10 of said bracket.

3. In a device of the character described, a shaft of angular cross-section, a bracket comprising a main part extending along said shaft and yokes at opposite ends of 15 said main part each having an angular opening in which said shaft non-rotatively slides, means for fixing one of said yokes to a support, a core fixed to the other yoke, a core

fixed to said shaft beyond the first core, and coils wound on the respective cores. 20

4. In a device of the character described, a shaft of angular cross-section, a bracket comprising a main part extending along said shaft and yokes at opposite ends of said main part each having an angular opening 25 in which said shaft non-rotatively slides, means for fixing one of said yokes to a support, a core fixed to the other yoke, a core fixed to said shaft beyond the first core, each core comprising a hub part by 30 means of which it is fixed to the yoke or shaft as the case may be, and comprising arms radiating from said hub part, and coils wound on the respective cores from side to side of the arms thereof.
